DISPENSING STRUCTURE

Edwin W. Lodge, Haddonfield, N. J., assignor of
one-half to Lowder T. Layton, Merion, Pa.

Application March 15, 1932. Serial No. 598,921

17 Claims. (Cl. 221—60)

My invention relates to closure members or caps for controlling delivery of fluids, semi-fluids or pastes, powders and the like, from containers, such as bottles, cans, compressible tubes 5 and the like, and more particularly to closure members or caps which are irremovable from the containers.

In accordance with my invention the closure member is rotatable upon and movable axially 10 or longitudinally of a spout, nipple or neck through which the material in the container is dispensed or discharged; the closure member, after predetermined movement longitudinally of the spout, reaches a position in which it coacts 15 with a detent or equivalent which limits its rotation with respect to the spout to an extent preventing withdrawal of the closure member from the spout, while permitting it to rotate to an extent to open or close a dispensing passage.

20 Further in accordance with my invention there is initially disposed between the spout and the closure member a gasket, disc or equivalent means, for sealing the discharge opening of the spout to prevent egress of material from the container, and the gasket or disc is of such thickness that, until its removal for initial use of the dispensing structure, it prevents the closure member taking the aforesaid position in which it is controlled by the aforesaid detent to prevent its 25 loss or removal from the spout.

25 Further in accordance with my invention means are provided for compressing or pinching the closure member to seal its discharge when the closure member is rotated from dispensing 30 position to position in which the discharge passage is closed.

35 My invention resides in the features of structure, arrangement and cooperation of the character hereinafter described and claimed.

40 My structure, while applicable to containers of various types aforesaid, is particularly useful in connection with collapsible or compressible tubes containing semi-fluids or paste, particularly tooth-paste, shaving cream, and the like.

45 For the purposes of description of my invention, my structure is, as hereinafter illustrated and described, applied to a collapsible or compressible tube.

50 For illustration of some of the various forms my invention may take, reference is to be had to the accompanying drawing, in which:

Fig. 1 is a vertical sectional view, partly in elevation, of structure embodying my invention;

55 Figs. 2 and 3 are views of the structure of

Fig. 1 with the cap in two further and successive positions;

Fig. 4 is a top plan view of the container and its spout, without the cap;

Fig. 5 is an elevational view, the spout partly 60 in section, of the container and spout, without the cap;

Fig. 6 is a vertical sectional view of the cap;

Fig. 6a is a bottom plan view of the cap;

Fig. 6b is a top plan view of the cap;

Fig. 7 is a plan view of the upper end of the spout;

Figs. 8 and 8a are, respectively, developments into a plane of the spout and the top of the container;

Fig. 9 is a vertical sectional view, partly in elevation, of a modified form of my construction;

Fig. 10 is a plan view of the lug supporting member of Fig. 9;

Fig. 10a is a sectional view taken on the line 75 X—X of Fig. 10.

Referring to Fig. 1, C is a container of soft or compressible metal such as tin, alloy, aluminum, or the like, and generically represents any container, of any material, whether rigid or compressible, including bottles, cans and the like. Upstanding from its top 1 is the cylindrical spout, neck or nipple 2, having the passage or bore 2a communicating with the interior of the container C and closed off at its upper end by an integral 80 diaphragm or plate 3 having the off center or laterally displaced dispensing orifice or slot 4. Upon the exterior of the spout 2 is formed the thread 5, or equivalent, with which meshes or coacts the thread 6, or equivalent, at the lower 90 portion of the cap or closure member 7, of metal, bakelite or the like. In the end or top 8 of the cap is provided a slot or aperture 9 adapted to be brought into register with the aforesaid aperture 4.

Within the upper end of the cap 7 is a disc or gasket, or equivalent means 10, of cork or other equivalent or suitable material, compressed between the end 8 of the cap and the end 3 of the spout, by screwing the cap downwardly upon the 100 spout. This gasket effectually seals the structure against egress of contents of the container C from the time the latter is filled or charged until its initial employment by the ultimate user.

In the lower end or face of the cap 7, as in its flange 11, is an arcuate slot 12.

The spout thread 5 terminates a substantial distance above the top 1 of the container. Between the lower end of the thread 5 and the top 1 is provided a thread 13, or equivalent, adapted 110

to mesh with the thread 6 on the cap after the thread 6 has passed downwardly off from and free of the thread 5. The thread 13 may have any suitable extent circumferentially of the neck 5 or spout 2, either less or greater than shown, and may be, as to position longitudinally of the spout 2, either in effect a continuation of the thread 5, or displaced from the thread 5 a distance different from the pitch or a multiple of the pitch 10 of the thread 5. In any event the longitudinal extent of the thread 6 on the cap 7 and the position of the thread 13 with respect to the lower end of the thread 5 are such that the thread 6 may pass off and be free from the thread 5 before 15 meshing with the thread 13.

Projecting upwardly from the container top 1, and suitably positioned circumferentially of the spout 2 with respect to the lower terminal of the thread 5, is a lug, detent or equivalent member 20 14, having any suitable shape, and if desired of greater extent circumferentially of the spout than shown, adapted to enter the aforesaid slot, groove or recess 12, whose wall at its ends preferably is at a great angle, as 90 degrees, with 25 respect to the lower end face of cap 7.

To place the structure in condition for first delivery of material from the container C through the passage 2a, and apertures 4 and 9, the user 30 unscrews the cap 7 from the spout 2, removes the disc or gasket 10, replaces the cap upon the spout 2 and by rotation threads it downwardly along the spout 2 until the thread 6 passes beyond and is free from the lower end of the thread 5, to a position illustrated by Fig. 2. In this position the 35 thread 6 is free of the spout, in the space between the thread 13 and the lower end of the thread 5. The cap is then rather loose upon the spout and its lower face or end abuts against the lug or 40 detent 14. At or adjacent this position the cap 7 is freely rotatable about the spout 2 without moving in either direction longitudinally thereof. The freedom of the cap 7 permits it to tilt over 45 slightly toward one side while in engagement with the lug 14 which holds the cap up with thread 6 against thread 5, though those threads are now no longer in mesh; after suitable rotation of the cap 7 while bearing on lug 14, the lug will enter and remain in the groove or channel 50 12, when the cap 7 can be righted to position coaxial with the spout 2, as generally indicated by Fig. 3, in which, however, the cap has been further rotated. Whatever resilience or yielding 55 there is or may be in the parts when the cap bears upon the lug, causes the lug on reaching slot 12 to spring into it and resist removal therefrom.

The cap now can be rotated through an arc which is restricted as to its extent by the arcuate 60 length of the groove or slot 12. With the lug 14 in the slot 12, it is impossible to rotate cap 7 to cause lug 14 to leave slot 12 as would be necessary again to bring thread 6 to position again to mesh with end of the thread 5. The cap is therefore 65 irremovable and is prevented from accidental loss, because it is in effect locked or prevented from removal from the spout 2.

The rotatable movement of the cap 7 when 70 thread 6 is free of both the threads 5 and 13, permits the aperture 9 in the cap 7 to be brought whereupon material may be dispensed from 75 container C; the apertures 4 and 9 come into register when one end of slot 12 comes into engagement with lug 14. Upon the return rotation of the cap 7 the aperture 9 is moved out of register

with aperture 4 and material can no longer be dispensed from the container. The rotation of the cap, when free of the threads 5 and 13 and while lug 14 is in slot 12, may be such as to bring the cap thread 6 into engagement with the thread 13, 80 the position indicated in Fig. 3, with the result that the cap 7 will be drawn downwardly as it is rotated, compressing or pinching its upper end 8 on to the end 3 of the spout, and at the limit of such movement the apertures 9 and 4 are out 85 of register, sealing the structure. The slot 12 is preferably of such length, and thread 13 so positioned, that in returning the cap from position in which apertures 4 and 9 register the thread 6 comes into mesh with thread 13 before lug 14 is 90 engaged by the other end of the slot, and completion of compression movement of the cap by action of threads 6 and 13 may be completed without said other end of the slot ever engaging lug 14.

It will be understood, however, that the thread 95 6 may be in mesh with the thread 13 throughout any suitable portion of the rotative movement of the cap permitted by the lug 14 and slot 12; the threads 6 and 13 may be in mesh throughout such portion of rotation of the cap 7 as to bring the 100 apertures 4 and 9 into and out of register, and beyond register to compress the cap upon the spout. As indicated in Fig. 3, the threads 6 and 13 are in mesh when the apertures 4 and 9 are not in 105 register.

The aperture 4, lower end of thread 5, thread 110 13, and lug 14 are in relative positions generally indicated in Figs. 7, 8 and 8a; the general relative positions of these parts are illustrated also by Figs. 4 and 5. The thread 5, spout 2, thread 13 and the top 1 of the container are shown developed into a plane, Figs. 8 and 8a; and the upper end of the thread 6, the aperture 9 and the slot 12 of the cap are positioned relatively to each other as generally indicated in Figs. 6, 6a and 6b, 115 whereby with the lug 14 in slot 12, the cap is irremovable, or may not be lost off from the spout 2, and yet may bring the apertures 4 and 9 into and out of register with each other, and, upon coaction with thread 13, may clamp or pinch the 120 upper end of the cap 7 down upon the upper end of the spout 2, tightly to seal the aperture 4 in the latter.

Fig. 2 illustrates the first stage in the more significant position of the cap, to wit, that in 125 which it is free of the spout and rotatable with respect thereto for opening and closing the dispensing passage, and in which it is restrained, by lug 14 on slot 12, from loss or remeshing with the spout. Fig. 3 illustrates an additional feature or 130 function of compression on the spout of the cap while the latter is still in the significant position of freedom of rotation with respect to the spout.

In Fig. 9 is shown a modification in the matter 135 of mounting of the lug or detent which engages in the cap slot 12. In this case there is provided a support 15, preferably of resilient metal, wire or sheet. Member 15 is separately illustrated in Figs. 10 and 10a at its inner end partially embracing or wholly surrounding the spout 2 which extends through the recess or hole 15a in member 15. At its other end member 15 is provided with a hole 15b which receives the post or lug 16 on the top of the container C. In brief, the member 15 is mounted upon a lug or post 16 whose upper end may be peened or worked over to prevent dislodgment. Laterally from the recess or hole 15a the member 15 is slotted, as indicated at 145 15c, 15c, to form a tongue 17 which is bent up to form the detent or lug 14' to enter and remain in 150

the cap slot or groove 12 to cooperate therewith as does the lug or detent 14 in Figs. 1-3. The member 15, or tongue 17, or both, are resilient, or yield under pressure of the cap 7 upon lug 14', the latter upon further rotation of the cap, as above described, entering and remaining in slot 12. The top 1 adjacent the tongue 17 may be provided with a depression 18, which may be formed by locally indenting the top 1, in the case it is of soft or readily deformable metal. This depression affords ample room for downward movement of the tongue 17 and its lug 14' when the bottom of the cap engages upon the lug 14' before the cap is rotated to position to permit the lug 14' to enter the slot 12.

The position of the parts indicated in Fig. 9 corresponds generally with the position indicated in Fig. 3.

As before, the cap 7 is rotated, within the limits permitted by the slot 12, to bring apertures 4 and 9 into and out of register; and again the thread 13 may be provided to mesh with the cap thread 6 during any suitable proportion of the rotation of the cap, and especially for compressing or pinching the upper end of the cap upon the upper end of the spout.

It shall be further understood of a construction generally of a character shown in Fig. 9 that the thread 5 upon the spout may be of such length that the cap thread 6 remains at all times in mesh therewith; in such case the cap may be first removed to remove the gasket 10, Fig. 1, and then threaded down upon the spout to a region in which the detent or lug 14' engages in the cap slot 12 in which it is then allowed to remain preventing the cap from such extent of rotation as to withdraw it upwardly upon the spout from said region but nevertheless permitting the apertures 4 and 9 to be brought into and out of register. In this case, while the cap remains threaded to the spout, its rotation with respect to the spout in said region after entry of the lug 14' into the slot 12 permits an action generally similar to that described in connection with Fig. 9. The length of the slot 12, however, may be such that upon screwing the cap still further down on the spout, its end 8 will be compressed or pinched against the end of the spout 2 with apertures 4 and 9 out of register, the lug 14' still remaining in the slot 12.

It will be understood of both modifications that the extra thread 13 upon the spout 2 is optional and not essential. If omitted, the cap 7 may nevertheless be rotated, within the limits permitted by lug in the slot 12, to bring the apertures 4 and 9 into and out of register. The thread 13, or any equivalent structure, when engaged by the cap serves to perform an additional function, viz., the compression of the upper end of the cap tightly upon the upper end of the spout.

Ordinarily a rotative movement of about 90° of the cap 7, with the lug 14 or 14' in the groove 12, is sufficient to bring the cap and spout apertures into and out of register; however, the slot 12 is of greater arcuate length than necessary for that purpose, to permit the cap thread 6 to mesh with the thread 13 and move thereon for compressing the upper end of the cap upon the upper end of the spout without bringing their apertures into register.

It will be understood that the lug 14 or 14' may be carried by the cap 7, and the coacting slot 12 may be formed in the top 1 of the container C.

It will further be understood that in lieu of the

threads 5 and 6 upon the spout and cap, there may be employed any other equivalent mutually meshing or cooperating formations on the spout and cap to effect relative movements and functions of the character hereinbefore described.

80

What I claim is:

1. In combination, a dispensing spout, a closure member therefor, said spout and member having mutually engaging formations, said closure member movable along said spout to a position where said formations disengage leaving the closure member free to rotate with respect to the spout to open and close a discharge passage, and means for retaining said closure member in said position to prevent return to position for re-engagement of said formations.

85

2. In combination, a dispensing spout, a thread thereon, a closure member having a thread meshing with the spout thread and passing off the latter to position in which the closure member is freely rotatable with respect to the spout to open and close a discharge passage, and means preventing remeshing of said threads.

95

3. In combination, a dispensing spout, a thread thereon, a closure member having a thread meshing with the spout thread and passing off the latter to position in which the closure member is freely rotatable with respect to the spout to open and close a discharge passage, said closure member having a slot, and a member extending into said slot when said closure member is in the position aforesaid, to prevent removal of said closure member from said spout.

100

4. In combination a dispensing spout, a thread thereon, a closure member having a thread meshing with the spout thread and passing off the latter to position in which the closure member is freely rotatable with respect to the spout to open and close a discharge passage, said closure member having a slot, and a member extending into said slot for limiting the rotation of said closure member in the position aforesaid.

110

5. In combination, a dispensing spout, a thread thereon, a closure member having a thread meshing with the spout thread and passing off the latter to position in which the closure member is freely rotatable with respect to the spout to open and close a discharge passage, said closure member having a slot, and a member extending into said slot for limiting the rotation of said closure member in the position aforesaid, said slot having an arcuate extent and positioned with respect to said closure member to prevent remeshing of said threads.

120

6. In combination, a dispensing spout, a thread thereon, a closure member having a thread meshing with the spout thread and passing off the latter to position in which the closure member is freely rotatable with respect to the spout to open and close a discharge passage, said closure member having a slot, a member engaged by said closure member during rotation of said closure member to position in which said member extends into said slot for retaining said closure member in said position.

125

7. In combination, a dispensing spout, a thread thereon, a closure member having a thread meshing with the spout thread and passing off the latter to position in which the closure member is freely rotatable with respect to the spout to open and close a discharge passage, said closure member having a slot, and a member engaged by said closure member and tilted thereby during rotation of said closure member to position in

130

135

140

145

150

which said member extends into said slot for retaining said closure member in said position.

8. In combination, a dispensing spout, a thread thereon, a closure member having a thread meshing with the spout thread and passing off the latter to position in which the closure member is freely rotatable with respect to the spout to open and close a discharge passage, said closure member having a slot, and a member engaged by said closure member and thrusting the thread of said closure member against said spout thread after said closure member reaches said position and during rotation of said closure member in said position, said member, upon further rotation of said closure member, entering said slot to retain said closure member in said position.

9. In combination, a container, a dispensing spout thereon, a thread on said spout, a closure member having a thread meshing with the spout thread and passing off the latter to position in which the closure member is freely rotatable with respect to the spout to open and close a discharge passage, said closure member having a slot, and a member fixed on said container extending into said slot, when said closure member is in the position aforesaid, to prevent removal of said closure member from said spout.

10. In combination, a container, a dispensing spout thereon, a thread on said spout, a closure member having a thread meshing with the spout thread and passing off the latter to position in which the closure member is freely rotatable with respect to the spout to open and close a discharge passage, said closure member having a slot, a member fixed on said container extending into said slot for limiting the rotation of said closure member in the position aforesaid, said slot having an arcuate extent and positioned with respect to said closure member to prevent remeshing of said threads.

11. In combination, a container, a dispensing spout thereon, a thread on said spout, a closure member having a thread meshing with the spout thread and passing off the latter to position in which the closure member is freely rotatable with respect to the spout to open and close a discharge passage, said closure member having a slot, a member yielding when engaged by said closure member and upon rotation of said closure member entering said slot for limiting the rotation of said closure member in the position aforesaid, said slot having an arcuate extent and positioned with respect to said closure member to prevent remeshing of said threads.

12. In combination, a container, a dispensing spout thereon, a thread on said spout, a closure member having a thread meshing with the spout thread and passing off the latter to position in which the closure member is freely rotatable with respect to the spout to open and close a discharge passage, a member embracing said spout and mounted on said container, and a detent member carried by said member and extending into said

slot, when said closure member is in the position aforesaid, to prevent removal of said closure member from said spout.

13. In combination, a dispensing spout, a thread thereon, a closure member having a thread meshing with the spout thread, removable means within said closure member for closing a discharge passage, said thread of said closure member, upon removal of said means, passing off of said spout thread to a position in which said closure member is freely rotatable with respect to the spout to open and close a discharge passage, and means for retaining said closure member in said position.

14. In combination, a dispensing spout, a thread thereon, a closure member having a thread meshing with the spout thread and passing off the latter to position in which the closure member is freely rotatable with respect to the spout to open and close a discharge passage, means for retaining said closure member in said position, and a second thread on said spout with which said thread of said closure member meshes for compressing said closure member upon said spout.

15. In combination, a dispensing spout, a thread thereon, a closure member having a thread meshing with the spout thread and passing off the latter to position in which the closure member is freely rotatable with respect to the spout to open and close a discharge passage, means for retaining said closure member in said position, and a second thread on said spout with which said thread of said closure member meshes for compressing said closure member upon said spout when said closure member is in position to close said discharge passage.

16. In combination, a dispensing spout, a thread thereon, a closure member having a thread meshing with the spout thread and passing off the latter to position in which the closure member is freely rotatable with respect to the spout to open and close a discharge passage, means for retaining said closure member in said position, a second thread on said spout with which said thread of said closure member meshes after pre-determined extent of rotation of said closure member in said position for compressing said closure member upon said spout.

17. In combination, a dispensing spout, a thread thereon, a closure member having a thread meshing with the spout thread and passing off the latter to position in which the closure member is freely rotatable with respect to the spout to open and close a discharge passage, means for retaining said closure member in said position, a second thread on said spout with which said thread of said closure member meshes after pre-determined rotation of said closure member in said position for compressing said closure member upon said spout when said closure member is in position to close said discharge passage.

EDWIN W. LODGE.
